UNITED STATES PATENT OFFICE.

HERMAN JUENGLING, OF DETROIT, MICHIGAN.

VALLEY-TILE.

1,217,459.

Specification of Letters Patent. Patented Feb. 27, 1917.

Application filed October 21, 1916. Serial No. 126,839.

To all whom it may concern:

Be it known that I, HERMAN JUENGLING, a subject of the Emperor of Germany, residing at Detroit, in the county of Wayne 5 and State of Michigan, have invented certain new and useful Improvements in Valley-Tiles, of which the following is a specification, reference being had therein to the accompanying drawings.

10 This invention relates to valley tiles, and the primary object of my invention is to provide tiles of the above character that are made entirely of concrete or other cementitious material and possess considerable 15 strength and rigidity with the same wearing qualifications as the ordinary baked or burnt tile.

Another object of my invention is to provide valley tiles that may be easily and 20 quickly laid to provide a non-leakable trough in the valley of a roof, and provision is made in connection with each tile to afford anchorage for overhanging or overlapping roof tiles adapted to border on the 25 valley tile. Provision is also made in connection with the valley tile to prevent the overflow of water at the longitudinal edges of the tiles, and since the tiles are to be made of concrete or similar plastic material, 30 it is possible to use any coloring matter in connection with the composition to impart a desired color or effect in connection with the valley tile.

The invention will be hereinafter specifically described and then claimed, and reference will now be had to the drawing, 35 wherein—

Figure 1 is a plan of a valley tile in accordance with my invention;

40 Fig. 2 is a longitudinal sectional view of the same;

Fig. 3 is an end view of a valley tile;

Fig. 4 is a perspective view of a portion of 45 a roof having valley tiles in accordance with my invention; and

Fig. 5 is a perspective view of overlapped valley tiles.

A valley tile is substantially V-shaped in cross section and provides inclined walls 1. 50 These walls, at one end of the tile, have the upper faces thereof cut away, as at 2 to provide a seat for the end of an adjoining tile, and the opposite end of the tile has the lower face thereof cut away as at 3, so that 55 said tile may overlap an adjoining tile, as best shown in Fig. 2. The remaining por-

tions of the walls 1 are of uniform thickness, and the upper faces of said wall are provided with longitudinal grooves 4 disposed in parallelism with the outer edges 60 of the wall and at points intermediate the outer edges of the walls and the bottom of the tile. These grooves serve a number of purposes. First, when a gutter is laid, the alining grooves serve as demarcations or 65 guide lines for the even laying of roof tiles that overlap the inclined walls of the gutter. Second, should such roof tiles have depending ribs at the lower edges thereof, said ribs can engage in the grooves and thus become 70 correctly positioned and anchored to a certain extent. Third, water is liable to accumulate in the crack or in the division space at the overlapping ends of the tiles and these grooves help carry off the water 75 before it can possibly back up and enter the roof sheathing.

The outer edges of the tile are provided with longitudinal ribs 5 and these ribs are adapted to prevent water from overflowing the longitudinal edges of a valley and support roof tiles on the edges of the valley tile.

It is preferable to curve or form the ends of the walls 1 on an arc, as indicated at 6, 85 as there is less chance of one tile becoming laterally displaced relative to the other and when said tiles are in overlapped registration, there is a greater bearing for one tile upon another, and the weight of the uppermost tiles will not tend to displace the lowermost tile.

The valley tiles can be easily and quickly molded from concrete and the body portion of each tile is of sufficient thickness to support the relative thin ends thereof adapted for overlapped registration with the ends of adjoining tiles.

One embodiment of my invention has been illustrated, but it is to be understood that 100 the structural elements are susceptible to such variations and modifications as fall within the scope of the appended claim.

What I claim is:—

105 A valley tile V-shaped in cross section and having the walls thereof provided with longitudinal grooves, intermediate the bottom center line of the tile and the side edges thereof, each wall of said tile at the upper end thereof being cut away on the upper 110 face to form a seat and provide relative thin end portion, the lower end of each wall

having the lower face thereof cut away to provide a relative thin portion adapted for overlapped registration with the relative thin portion of an adjoining tile, said tile having the end portions thereof described on an arc to afford a large bearing for adjoining tiles, and the grooves of the tile extending from the seats at the upper end

of the tile to the edge of the lower thin portion of the tile.

10

In testimony whereof I affix my signature in the presence of two witnesses.

HERMAN JUENGLING.
